ATTORNEY

UNITED STATES PATENT OFFICE

ALFRED W. BRUCE, OF NEW YORK, N. Y.

AUXILIARY APPARATUS FOR STEAM GENERATORS

Application filed August 13, 1929. Serial No. 385,659.

This invention, more particularly, relates to economizers and associated superheaters adapted for use with high pressure steam generators for locomotives.

5 An object of the present invention is to provide, an economizer of simple, durable and compact construction, which can be economically manufactured and maintained, and which is highly efficient in operation.

10 Another object of the invention is to provide a combined economizer and superheater, of simple, economical and compact construction, and of high efficiency in operation. Other objects of the invention will herein- 15

after readily appear.

The improvement claimed is hereinafter fully set forth.

In the accompanying drawings: Figure 1 is a side elevation with portions broken away

20 of a combined economizer and superheater embodying the invention; Fig. 2, a fragmentary end view of the construction shown in Fig. 1, two of the vertical rows of economizer and superheater tubes being shown; Fig. 3,

25 a fragmentary view in horizontal section taken on the line III—III, of Fig. 1; and, Fig. 4, a fragmentary view, partly in horizontal section taken on the line IV—IV of Fig. 1.

30 In the practice of the invention referring descriptively to the specific embodiment thereof which has been selected for exemplification herein, the economizer comprises a plurality of superposed longitudinal water

35 tubes 10, arranged in parallel vertical rows. The tubes of each row are connected at one end in pairs by return bends 10a. At the other end the lower tube of the bottom pair is connected to a header compartment 11, the upper

40 tube of that pair is connected to a header compartment 11a, to which compartment the lower tube of the next superposed pair is also connected. This general arrangement is followed throughout each of the vertical rows.

45 Each water tube 10, has concentrically extending therethrough, a fire tube 12. Thus a water space 13, circular in cross-section is provided between each water tube and each fire tube. The lower header compartment

50 11, of each row is connected to a separate in-

take pipe 14, which may be connected to a suitable common header, not shown, or if desired to an individual feed pump. Also if desired a separate valve may be provided for closing off any of the intake pipes 14, to insure efficient blowing-off of the tubes. The top header of each row is connected to a discharge pipe, 15, which communicates with a common header 16. A separate valve 17, is provided at the header 16, for each of the discharge pipes 15, so that the tubes of any desired rows may be closed off selectively to facilitate efficient blowing-off.

From the foregoing description, it will be obvious that water circulates through all of the water tubes 10, of each row in a continuous path leading from the lowermost water tube of each row through the uppermost tube thereof.

It is to be noted that each of the superposed pairs of water tubes is made of shorter length than the pair next below so that at the return bend end of the economizer, the pairs of tubes of each row are stepped to provide for economy of space for the application of the superheater tubes. While each of the header compartments 11a, is formed as a separate unit adapted to connect two superposed pipes of different pairs, it is within the contemplation of the invention to utilize 70 constructions wherein the header compartments are divisions of larger units.

Hollow cylindrical fittings are screw threaded in the headers 11 and 11a, one for each fire tube. These fittings serve to seal the headers so as to permit the passage of the fire tube, but to prevent escape of the circulating water.

The superheater comprises a common header 18, which may be formed with the usual saturated and superheated steam compartments; and a plurality of steam circulation tubes 18a.

It is to be noted that the vertical reaches 18b and 18c of the respective steam circulation tube units are made progressively shorter, those leading to the bottom fire tubes being the longest, and those leading to the top fire tubes being the shortest. This form 95 of superheater tubes in conjunction with the 100 105

progressively shortened tubes of the economizer, provides a compact construction effecting a considerable saving of space in the locomotive superstructure.

5 While one of the preferred forms of construction has been described and shown, it is obvious that many variations in procedure, form, arrangement, and construction of parts, may be resorted to, and the invention, therefore, is not limited to the particular embodiment disclosed, but includes such changes and modifications as come within the spirit and scope of the invention as set forth in the appended claims.

15 The invention claimed and desired to be secured by Letters Patent, is:

1. In an apparatus for locomotives, the combination of an economizer comprising a plurality of superposed water tubes arranged in vertical rows, the tubes of each row being connected at their rear ends in pairs by separate, spaced, return bends to permit the flow of combustive gases longitudinally between said tubes, means for connecting the 20 opposite ends of the tubes to permit the circulation of water therethrough, and a plurality of fire tubes each passing through one of the water tubes.

2. In an apparatus for locomotives, the combination of an economizer comprising a plurality of superposed longitudinal water tubes arranged in vertical rows, the tubes of each row being connected for communication at their rear ends by separate, spaced, couplings to permit the flow of combustive gases longitudinally between said tubes, header compartments at the other end of the tubes, each compartment coupling for communication one tube of one pair with one tube of another pair, and a plurality of fire tubes, each passing through one of the water tubes.

3. In an apparatus for locomotives, the combination of an economizer comprising a plurality of superposed longitudinal water tubes, arranged in vertical rows, the tubes of each row being connected at their rear ends in pairs by separate, spaced, return bends to permit the flow of combustive gases longitudinally between said tubes, header compartments at the other end of the tubes, each compartment coupling for communication one tube of one pair with one tube of another pair, and a plurality of fire tubes, each passing through one of the water tubes.

4. In an apparatus for locomotives, the combination of an economizer comprising a plurality of superposed longitudinal water tubes arranged in rows with the tubes of each row connected at their rear ends in pairs by separate, spaced, return bends to permit the flow of combustive gases longitudinally between said tubes, means for connecting the opposite ends of the tubes to permit the circulation of water therethrough, and a plurality of fire tubes each passing through one

of the water tubes; and a superheater comprising a header and a plurality of steam circulation tubes extending into the fire tubes of the economizer.

5. In an apparatus for locomotives, the combination of an economizer comprising a plurality of superposed longitudinal water tubes arranged in rows with the tubes of each row connected at their rear ends in pairs by separate, spaced, return bends to permit the flow of combustive gases longitudinally between said tubes, means for connecting the opposite ends of the tubes to permit the circulation of water therethrough, and a plurality of fire tubes, each disposed substantially concentric of and passing through one of the water tubes, and a superheater comprising a header and a plurality of steam circulation tubes extending into the fire tubes of the economizer.

6. In an apparatus for locomotives, the combination of an economizer comprising a plurality of superposed water tubes arranged in vertical rows, the tubes of each row being connected at their rear ends in pairs by separate, spaced, return bends to permit the flow of combustive gases longitudinally between said tubes, means for connecting the opposite ends of the tubes to permit the circulation of water therethrough, and a plurality of fire tubes each passing through one of the water tubes; and a superheater comprising a header and a plurality of steam circulation tubes extending into the fire tubes of the economizer.

7. In an apparatus for locomotives, the combination of an economizer comprising a plurality of superposed longitudinal water tubes arranged in vertical rows, the tubes of each row being connected at their rear ends in pairs by separate, spaced, return bends to permit the flow of combustive gases longitudinally between said tubes, header compartments at the other end of the tubes, each compartment coupling for communication one tube of one pair with one tube of another pair, and a plurality of fire tubes, each passing through one of the water tubes, and a superheater comprising a header and a plurality of steam circulation tubes extending into the fire tubes of the economizer.

8. In an apparatus for locomotives, the combination of an economizer comprising a plurality of superposed longitudinal water tubes, arranged in vertical rows, the tubes of each row being connected at their rear ends in pairs by separate, spaced, return bends to permit the flow of combustive gases longitudinally between said tubes, header compartments at the other end of the tubes, each compartment coupling for communication one tube of one pair with one tube of another pair, and a plurality of fire tubes, each passing through one of the water tubes; and a superheater comprising a header and a plu-

rality of steam circulation tubes extending into the fire tubes of the economizer.

9. In an apparatus for locomotives, the combination of an economizer comprising a plurality of superposed water tubes arranged in vertical rows, the tubes of each row being connected at one end in pairs by return bends, means for connecting the opposite ends of the tubes to permit the circulation of water therethrough, and a plurality of fire tubes each passing through one of the water tubes, the pairs of water tubes at one end being made successively shorter; and a superheater comprising a header and a plurality of steam circulation tubes, each formed with an upstanding portion adjacent the header, and a portion extending into a fire tube of the economizer.

10. In an apparatus for locomotives, the combination of an economizer comprising a plurality of superposed water tubes arranged in vertical rows, the tubes of each row being connected at one end in pairs by return bends, means for connecting the opposite ends of the tubes to permit the circulation of water therethrough, and a plurality of fire tubes each passing through one of the water tubes, the pairs of water tubes at one end being made successively shorter; and a superheater comprising a header and a plurality of steam circulation tubes, each formed with an upstanding reach, a reach leading into one of the fire tubes, a return bend within the fire tube, a reach leading out of the fire tube, a return bend leading to a second fire tube, a reach leading into that fire tube, a return bend within the second fire tube, a reach leading out of the second fire tube, and a second upstanding reach leading to the header.

40 11. In an apparatus for locomotives, the combination of an economizer comprising a plurality of superposed longitudinal water tubes arranged in rows with the tubes of each row connected at their rear ends in pairs by separate, spaced, return bends to permit the flow of combustive gases longitudinally between said tubes, means for connecting the opposite ends of the tubes to permit the circulation of water therethrough, and a plurality of fire tubes each passing through one of the water tubes.

ALFRED W. BRUCE.
